UNITED STATES PATENT OFFICE.

EPHRAIM L. BEARSE, OF BROOKLYN, NEW YORK.

DESIGN FOR A BURNER.

SPECIFICATION forming part of Design No. 23,035, dated February 6, 1894.

Application filed May 15, 1893. Serial No. 474,353. Term of patent 7 years.

to all whom it may concern:

Be it known that I, EPHRAIM L. BEARSE, of Brooklyn, in the county of Kings, State of New York, have originated and produced a Design for a Burner or Similar Article, of which the following is a full, clear, and exact description, reference being had to the accompanying drawing, forming a part of this specification.

The essential features of my present design are the hand like configuration extending up from a sleeve-like base and with the fingers clasped around a downwardly extending fluted stem of a flamboyant torch, the representation of the latter being completed by the fluted dish or saucer configuration with the spiral configuration representing an upwardly leaping flame.

In the accompanying illustration the hand A is represented as a right hand, with the fingers clasped partially around a tapered and fluted torch stem B. This stem is exposed throughout its length, terminates at the

bottom in a rounded knot or ornamentation C, and is surmounted by a saucer or dish-shape configuration D, fluted spirally on the under side. The upwardly leaping flame representation D' is given a spiral configuration terminating in points d at the top. The stem of the torch is further ornamented by diagonal crossed bands E representing ribbon wound about the same.

The details of the design render it very harmonious and pleasing, the position of the hand being such as to indicate that the torch is held lightly and easily, as contradistinguished from a grip which would give the design a hard, firm character.

What I claim is—

The design for a burner herein described and illustrated in the accompanying drawing. 40

EPHRAIM L. BEARSE.
